UNITED STATES PATENT OFFICE.

HENRY EDMUNDS, JR., OF NEW YORK, N. Y., ASSIGNOR TO THOMAS J. MONTGOMERY, OF BOSTON, MASSACHUSETTS.

CONTACT FOR ELECTRIC LAMPS.

SPECIFICATION forming part of Letters Patent No. 288,217, dated November 13, 1883.

Application filed April 5, 1883. (No model.)

To all whom it may concern:

Be it known that I, HENRY EDMUNDS, Jr., of the city and State of New York, have invented an Improvement in Contacts for Electric Lamps, of which the following is a specification.

This improvement relates to a peculiar spring-contact that is employed for incandescent electric lamps to close or break the circuit by a partial rotation of the base of the lamp.

In the drawings, Figure 1 is an elevation of the lamp complete. Fig. 2 is a section of the base. Fig. 3 is an inverted plan of the base, and Fig. 4 is a plan of the cup.

The electric lamp A is of any desired construction. I have shown the same as provided with a coiled filament within a glass globe that is supported by a spring, c, above the base B, and the spring-hooks d form the conductors within the base B.

The metallic cup F, with its inclosed insulating block S, is screwed upon the tubular support G, and within the cup and upon the upper surface of the block S are the contact plates l l', having studs o o' projecting up from the faces, and these contact-blocks are attached by screws i, which also serve to clamp the naked ends of the insulated conductors k, that pass through the tube G.

Upon the under surface of the base B there are the spring-contact plates n n', and the conductors d are connected with these spring-contacts by being passed around under the screw heads and clamped thereby. The lower end of the base B enters into the cup F, and there is a shoulder at 2 around this base, and a helical spring, p, is introduced between the top

edge of the cup F and this shoulder 2. There is a tubular case, m, around the cup F and base B. At the lower part it is attached to the cup F by screws 3 or by bayonet-lock pins 4, and screws 3, to prevent the parts turning, and to allow for said parts being separated when necessary. In the upper part of the case m there are slots 5 placed diagonally, and screws 6, passing into the base B. By this construction I am able to turn on the current by giving the base B a partial rotation. In the normal position of the parts, with the screws 6 at the upper ends of the slots 5, the electric lamp is raised in the position indicated by dotted lines, Fig. 1, and the springs n n' are out of contact with the studs o o', and hence the circuit is broken. When the base B is partially revolved, so as to bring the parts into the positions shown by full lines, the screws 6, passing down the inclines of the slots, bring the springs n n' into contact with the studs o o' by a sliding motion that insures perfect metallic contact, and also keeps the surfaces clean.

I claim as my invention—

The combination, with the electric lamp A, and its base B, of the cup F, the spring p between the upper end of the cup and the base, the case m, attached to the cup, and having inclined slots, the pins or screws 6, the spring-contacts n n', the plates l l', and studs o o', and the electric conductors k, substantially as set forth.

Signed by me this 29th day of March A. D. 1883.

HENRY EDMUNDS, JR.
